United States Patent Office.

WILLIAM H. CLARKE, OF ST. ANTHONY'S FALLS, MINNESOTA.

Letters Patent No. 63,215, dated March 26, 1867.

IMPROVED APPARATUS FOR CARBURETTING AIR, &c.

The Schedule referred to in these Letters Patent and making part of the same,

TO ALL WHOM IT MAY CONCERN:

Be it known that I, WILLIAM H. CLARKE, of St. Anthony's Falls, in the county of Hennepin, and in the State of Minnesota, have invented certain new and useful Improvements in Portable Gas Machines, and do hereby declare that the following is a full, clear, and exact description thereof, reference being had to the accompanying drawings, and to the letters of reference marked thereon. In the annexed drawings, making part of this specification—

A represents a cylinder made of suitable size, with a closed bottom and open top. Within this cylinder is another, B, which is made several inches smaller in diameter. C represents a float, which is closed at top and open at bottom, and which fits loosely over the inner cylinder B. The space between the two cylinders is filled with any suitable solution. The float C is provided at its upper end with two arms which carry friction-rollers, and these rollers run against the upright guides E E. The object of this arrangement is to steady the float, and support and direct its upper end as it rises and falls between the two cylinders. Within the cylinder B are fitted and soldered properly three or more annular metallic plates, I. These plates are placed at a proper distance apart, and are intended for receiving upon their upper surfaces the gasoline to be converted into gas. Each plate is provided with four or more short pipes, b b, whose lower ends turn in towards the centres of the plates. These pipes are for the purpose of transmitting air from the chamber D to the gasoline upon the plates I I. K represents a pipe, which runs from a bellows, T, up through the bottom of cylinder A, and up through the plates I at their centres, and is for the purpose of conveying air into the chamber D, from said bellows. H represents a pipe which runs up through the bottom of cylinder A, and through the plates I, curves, and comes down again through said plates and through the bottom of cylinder A, and there terminates. This pipe is made of copper, and is for the purpose of carrying heat into the machine. A burner, at q, belonging to a gas pipe, P, sets under one end of this pipe, and its heat passes into the pipe and thence through it, heating the inside of the machine. M M represent supply pipes, through which gasoline is introduced into the machine. There is one pipe, M, to each plate I, so that when it is desired to deliver the gasoline upon any specified plate it is poured into the corresponding pipe M of said plate. These pipes M run a short distance above the upper surfaces of the plates, as seen. L L are pipes which also run into the machine, and through the plates I, with their ends terminating on a level with the upper surfaces of the said plates. These pipes L are for the purpose of carrying off any residuum from the plates. J J are short pipes which pass through each plate separately, not passing through two of the plates. These pipes run a short distance above and below the plates, and are for the purpose of transmitting the gas below the plates so that it can pass off to a purifier, O, through a channel, X. O represents a tank or purifier, which is connected to the cylinder A by means of a channel or pipe, X. This tank is provided with a man-hole at S, which is secured in any approved manner, and also with a pipe, R, which conveys the gas away to any desired point to be used. Connected to this pipe R is the pipe P, which receives enough gas from the tank to supply heat to the machine. V represents a shaft, supported upon a frame connected to the machine, which said shaft has connected with it a spring and suitable gearing to give motion to a pitman, U, which operates the bellows. W represents a rod with a pawl attached to it, which said pawl is intended to work in connection with a ratchet-wheel which is used with the gearing. A rod, G, which plays up and down with the float C, is provided with two pins, or their equivalent, which act at suitable times upon the rod W, and cause it to throw the gearing in or out of connection with the pitman. When the float has been pumped full of air and rises as high as it is designed to go, the one pin on rod G operates the rod W so as to throw the gearing out of connection with the pitman and thus stops the pump. When the float falls as far down as it is designed to go, the other pin on rod G throws the gearing in connection with the pitman, and the bellows being set in motion the float is filled with air again. This arrangement of machinery may be varied, and does not necessarily form a part of this machine or invention. I may use a weight instead of a spring to run the gear-wheels by. In using this invention the gasoline or other material is poured in through the pipe M, and is properly distributed upon the plates I. The air being forced into chamber D, through pipe K, by means of the pump or bellows T, is driven down by the weight of the float C, through the pipes b b, and is thus brought into contact with the gasoline. The hot air or heat created by the pipe H converts the gasoline into gas, and said gas passes off through pipes J J, and through pipe X, to the purifier or tank O. Within the tank O, lime or any other

suitable substance is placed for the purpose of purifying the gas. A layer of cotton is introduced into the tank for breaking the force of the gas.

Having thus fully described my invention, what I claim, is—

1. The arrangement of the plates I I, in the cylinder B, and providing the same with air pipes b b, supply pipes M M, discharge pipes L L, and gas-transmitting pipes J J, substantially as and for the purpose specified.
2. The combination of the cylinders A and B, float C, bellows T, and tank O, provided with lime and cotton, substantially as and for the purpose specified.
3. The arrangement of the pipe H with the pipe P for supplying heat to the machine from its own gas, substantially as specified.

In testimony that I claim the foregoing invention of a portable gas machine I have hereunto set my hand and seal this day of January, 1867.

WILLIAM H. CLARKE.
